UNITED STATES PATENT OFFICE.

ENOCH E. NEAL, OF MALDEN, MASSACHUSETTS.

FASTENING DEVICE FOR COAL CHUTES.

Application filed October 27, 1921. Serial No. 510,907.

To all whom it may concern:

Be it known that I, ENOCH E. NEAL, a citizen of the United States, residing at Malden, in the county of Middlesex and State of Massachusetts, have invented new and useful Improvements in Fastening Devices for Coal Chutes, of which the following is a specification.

This invention relates to a fastening device for coal chutes and the like, and has for its object to provide a device through the medium of which the sections of a telescoping coal chute may be easily and quickly secured together in the event of more than one 15 of said sections being required to complete a chute of the length desired.

Another object of the invention is to provide a device adaptable for use upon the different types of coal chutes in common use. 20 The invention consists in the combination and arrangement of parts set forth in the following specification and particularly pointed out in the claims thereof.

Referring to the drawings:

25 Figure 1 represents a plan view of a portion of two sections constituting a telescoping coal chute, said sections being secured together by a device embodying my invention.

Fig. 2 is a transverse section partly in 30 elevation taken on the line 2--2 of Fig. 1 and looking toward the right in said figure.

Fig. 3 is a view similar to Fig. 2 but illustrating a different construction of coal chute and illustrating the manner in which the 35 fastening device is applied thereto.

Like numerals refer to like parts throughout the several views of the drawings.

In the drawings, referring particularly to Figs. 1 and 2, A and B represent the sections of a telescoping coal chute C, said sections being identical in construction and adapted to fit closely one within the other when completely telescoped in the usual well known manner. The sections A and B each 45 comprise a runway constructed of sheet metal having a bottom 5 and side walls 6, the said bottom being widest at an end a and gradually decreasing in width from said end toward the opposite end b, while the 50 side walls 6 are highest at the end a and also gradually decrease in height from the end a toward the end b. The side walls 6 of each section are reinforced by angle irons 7 which extend the length of each section, 55 and downward projecting flange 8 being riveted to the outer surface of each side wall 6 adjacent to the upper edge thereof and another flange 9 projects inwardly from said side. The opposite ends of the sections A and B are strengthened by reinforcing members 10 and 11 located at the ends a and b respectively. The reinforcing member 10 extends across the under side of the bottom 5 and has upwardly projecting arms 12 to which the sides 6 are secured. The upper 60 ends of the arms 12 project inwardly at 13 and are secured to the inwardly projecting flanges 9 of the angle irons 7 and at one side of each section the projections 13 are extended a short distance beyond the inner edge 70 of the flange 9 and are then bent downwardly at 14 to form a stop for the purpose of holding one of the angle irons 7 of one section beneath the corresponding angle iron 7 of the other section when said sections are 75 secured together as illustrated in Figs. 1 and 2. As the sections A and B are moved one upon the other to vary the overall length of the chute C the side walls 6 upon the upper side of Fig. 1 or at the left hand side 80 of Fig. 2 are always held in the same relative position to each other. The distance between the side walls 6 at the bottom of Fig. 1 or at the right hand side of Fig. 2, however, varies as the section B is moved 85 within the section A, and as the angle irons 7 of said sections cannot co-operate to hold the last mentioned sides together after the sections have been moved one upon the other beyond a certain limit, some other means is 90 required for performing this function. This means which also constitutes the novel feature of this invention, comprises a flexible member, preferably a chain 15 having a plurality of links to the lower of which a hook 95 16, of any desired construction, is attached. The hook 16 is constructed and arranged to engage a downwardly projecting flange 23 of the reinforcing member 10 as illustrated in Fig. 2. At its other end the chain 15 has 100 an elongated link 17 in which a member 18 is secured, the link passing through an opening 19 in said member. The member 18 is provided with oppositely disposed hook portions 20 and 21, the hook 20 being adapted 105 to engage the flange 9 of the angle iron 7, while an edge 22 of said member 18 rests upon the flange 9 as illustrated in Fig. 2. The opening 19 is so positioned within the member 18 that when the hook portion 20 is 110 positioned upon the flange 9 the chain 15 will hang beside the outer surface of the side

wall 6 of the chute section B and the hook 16 is then attached to the flange 23. Where the chute sections are constructed as illustrated in Figs. 1 and 2 and are prevented from separating from one side thereof by the downwardly extending portion 14 of the projection 13 of the reinforcing member 10 only one fastening device is required. If, however, the chute sections are not constructed 10 with the before-mentioned projection 14 two fastening devices may be utilized, each being attached in a similar manner to opposite sides of the chute sections.

The hook portion 21 is formed somewhat differently from the portion 20 and is provided for the purpose of being utilized when the chute sections are provided with rolled edges as illustrated in Fig. 3. In this figure chute sections D and E have side walls 25, 20 the upper edges of which are reinforced by being rolled in any suitable manner as at 26. In such cases the member 18 is turned 25 within the link 17 to the position illustrated in Fig. 3, at which time the rear of the hook portion 20 will engage a link 27 of the chain 15 and thereby position the hook portion 21 to engage the rolled edge 26. The chain 15 hangs adjacent to the outer surface of the side walls 25 and the hook 16 is attached 30 to a flange 28 of a reinforcing member 29 as previously described in connection with Figs. 1 and 2. When chute sections are constructed as are the sections D and E two fastening devices are required to secure 35 said sections together.

The general operation of my improved fastening device is as follows:—When it is found that one of the sections A or B is not long enough to deliver the coal to the 40 point desired two or more of the sections are placed together as illustrated in Figs. 1 and 2. The chute C is then placed in an inclined position and the highest end thereof supported in any desirable manner. In 45 this position the end b of the section B will contact with the bottom 6 of the section A and at one side the angle iron 7 of the section B is located beneath the angle iron 7 of the section A with the upper surface of 50 the lower angle iron contacting with the under corner of the upper angle iron at the left hand extremity of the section A, Fig. 1. In this position the projection 14 will prevent the side walls 6 at the left hand 55 side of Fig. 2, from moving further apart. The member 18 is then placed upon the flange 9 of the angle iron 7 with the hook portion 20 thereof engaging the inner edge of said flange. The chain 15 now hangs adjacent to the outer surface of the side wall 60

6 and the hook 16 at the lower end of said chain is secured to the flange 23 of the reinforcing member 10. The chute sections A and B are now fastened securely together with the chute C ready for use. Where the construction of the chute sections differs and the hook portion 20 of the member 18 cannot be used, the hook portion 21 is utilized as illustrated in Fig. 3.

The device as illustrated and described is 70 extremely simple, easy to operate and cannot be damaged by hard usage. When not in use it may be carried upon the coal truck or within the pocket of the workman.

It will be evident that it is not necessary 75 to use similar chute sections in the formation of the completed coal chute, as the fastening device may be used equally well with odd sections no matter what their construction may be provided there are flanges 80 thereon to which the hooks may be attached.

I claim:

1. A fastening device for coal chutes having, in combination, a flexible member, a hook attached thereto at one end thereof and a member attached to said flexible member at the other end thereof provided with a plurality of oppositely disposed hook portions of different contours formed integral therewith.

2. A fastening device for coal chutes having, in combination, a flexible member, a hook attached thereto at one end thereof and a member attached to said flexible member at the other end thereof provided with a plurality of oppositely disposed hook portions formed integral therewith, one of said hook portions being adapted to contact with said flexible member and thereby position 100 the other hook portion upon said flexible member.

3. A device of the character described having, in combination, a chain embodying therein a plurality of links, a hook attached 105 to a link at one end of said chain and a member attached to a link at the other end of said chain and embodying therein a plurality of hook portions, one of said hook portions being adapted to swing into engagement with a link of said chain and thereby position the other hook portion 110 upon said chain.

In testimony whereof I have hereunto set 115 my hand in presence of two subscribing witnesses.

ENOCH E. NEAL.
